UNITED STATES PATENT OFFICE.

ROSCOE B. SHIFFNER, OF KANSAS CITY, MISSOURI.

CARBOY LIFT.

Application filed May 4, 1921. Serial No. 466,646.

To all whom it may concern:

Be it known that ROSCOE B. SHIFFNER, a citizen of the United States of America, residing at Kansas City, in the county of Jackson and State of Missouri, has invented new and useful Improvements in Carboy Lifts, of which the following is a specification.

The object of the invention is to provide a relatively simple and efficient means where-
10 by carboys and like containers ordinarily employed for the storage and transportation of acids used in various arts and manufactures may be lifted, moved and tilted to discharge their contents under conditions con-
15 venient to the operator without involving any considerable effort and without subjecting the operator to the risk of spilling or wasting the contents of the receptacle or of becoming splashed thereby; and more par-
20 ticularly without involving the risk of breaking the container which usually is made of glass as a material best adapted to resist the action of the contents; and with these ob-
25 jects in view the invention consists in a con-
struction and combination of parts of which a preferred embodiment is shown in the accom-
pany drawings, wherein:—

Figure 1 is a side view of a carboy lift and cradle constructed in accordance with the invention, a carboy being shown seated thereon.

Figure 2 is a rear view of the same.

Figure 3 is a side view in carboy receiving position.

35 The apparatus embodies essentially a platform or seat 10 for the carboy which is shown at 11 and is carried by parallel rockers 12 connected by transverse strips 13 forming said seat and strips 14 forming a back, said seat and back being arranged in perpendicular relation to receive the carboy, handles 15 being arranged on opposite sides of the seat in a plane about midway of the depth of the seat and being braced near its 40 upper end by a bar 16 connected with one of the rockers, a further diagonal brace 17 being arranged upon each rocker in intersecting relation with the angle between the seat and the back to strengthen the structure.

50 The rockers are preferably shod at their bearing edges as indicated at 18 with strap iron or the equivalent thereof, when as may be preferred the body portions of the rockers are constructed of wood, as a means of in-
55 creasing the durability thereof and the facility with which the carboy can be bodily

moved over a supporting surface such as the floor.

Moreover the rockers may as shown be provided at their normal lower ends, in par-
60 allelism with the seat 10 with a flat bearing surface 19 upon which the structure may be supported as the carboy is being placed thereon, the latter being tilted away from the cradle so as to incline the bottom thereof suffi-
65 ciently to be arranged on the front edge of the seat, after which the carboy can be slid forward until it comes into contact with the back represented by the transverse strips 14. A retainer of flexible material such as 70 chain is indicated at 20, the same consisting of members attached at their lower ends as at 21 to the portions of the rockers beneath the seat and thence being extended upward substantially paralleled with the handle 15 75 and interlocked at their upper ends above the top of the carboy by means of a hook and eye or equivalent fastener as indicated at 22. This retainer serves to prevent the movement of the carboy in a direction parallel with the 80 back when tilted to the discharging or emptying position indicated in dotted lines in Figure 1. The seat provided for the reception of the carboy is preferably provided with metallic runners 10^a consisting of metallic strips serving to facilitate the sliding movement of the carboy in positioning the 85 same on the cradle.

The portions of the bearing edges of the rockers between the points *a* and *c* are curved 90 and may as shown be struck from a common center which in the construction illustrated is indicated at *d* at or about a vertical plane of the centers of the carboy and above the plane of the center of the height or mid-
95 depth of the carboy, such mid-depth being indicated by the dotted line *e*, so that the height of the rocker from *f* to the line *e* representing the mid-depth of the carboy is about in the proportion of three to four to 100 the portion of the height of the rocker between the line *e* and the point *c*.

The curve of the bearing edges of the rockers having its center slightly above the mid-depth of the carboy and hence slightly 105 above the center gravity of the carboy and its contents, the tendency of the cradle is to assume an inclined position approximating that shown in Figure 1 with the portions of the rockers about opposite the angle 23 110 constituting the neutral rest to which the cradle returns upon being tilted in either

direction therefrom, and the curve of which this bearing point constitutes the approximate center is that of which the brace 17 represents the chord, so that the seat and back provided for the reception of the carboy, in the normal or neutral position of the cradle diverge upwardly on planes substantially at equal angles from the plane of the horizon.

10 A further consequence of the arrangement and relative disposition of the parts indicated is that in tilting the cradle forward to discharge more or less of the contents of the carboy into a receptacle provided for the 15 purpose, a downward pressure upon the handle 15 is necessary throughout the operation and regardless of the extent to which the contents of the carboy have been discharged, so that upon release of the handle 20 or removal of pressure therefrom the cradle immediately swings back to the neutral position and thus assumes a condition of stable equilibrium with the carboy in position to prevent discharge of the contents, whether 25 the top of the carboy is plugged or sealed or not, the usual stopper 24 being provided for preventing evaporation of the contents.

Notwithstanding the stable construction of the device, however, it will be obvious 30 that it may be tilted in one direction or the other, to either permit of the placing or displacing of a carboy with relation to the seat or to pour the contents of the carboy from the unstopped neck, with a comparatively slight effort on the part of the operator.

To support the cradle in a position to per-

mit of the seating of a carboy it is preferably provided with standards or legs 25 pivoted as at 26 to the rockers and adapted 40 either to be extended as shown in full lines in Figure 3 or folded as indicated in dotted lines.

Having described the invention, what is claimed as new and useful is:—

45 A carboy cradle comprising a pair of parallel rockers having outer rounded bearing edges and cut away at the rear to form a normally horizontal edge and a normally vertical edge, transverse strips connecting 50 both the normally vertical and normally horizontal edges to provide, respectively, a seat and a back, of which the former is adapted for the reception of a carboy, diagonal braces spanning the rockers in intersecting relation with the angle between the seat and the back, handles secured to the rockers on opposite sides of the seat in a plane midway the depth of the seat, brace bars disposed in parallelism with the seat 60 and connecting the handles with the rockers adjacent the upper ends of the former, legs pivotally connected with the rockers and adapted to maintain the device in upright position when the seat is disposed in a horizontal plane, and a flexible retainer consisting of detachably connected chains having their extremities secured respectively to the two rockers and adapted for spanning relation with a carboy carried on said seat.

70 In testimony whereof he affixes his signature.

ROSCOE B. SHIFFNER.
